UNITED STATES PATENT OFFICE.

EDWARD P. ERICSON, OF CLERMONT, IOWA.

FRUIT OR VEGETABLE STEAMER.

SPECIFICATION forming part of Letters Patent No. 468,499, dated November 17, 1891.

Application filed October 2, 1890. Serial No. 366,842. (No model.)

To all whom it may concern:

Be it known that I, EDWARD P. ERICSON, a citizen of the United States, residing at Clermont, in the county of Fayette, State of Iowa, have invented certain new and useful Improvements in Fruit or Vegetable Steamers, of which the following is a specification, reference being had therein to the accompanying drawings.

10 This invention relates to certain new and useful improvements in steamer attachments for boilers and the like, designed more particularly for use in the canning or preserving of fruits or vegetables.

15 The object of the invention is to provide a simple and cheap attachment which may be readily inserted in a common wash-boiler, and upon which the jars or cans are designed to be supported by the attachment, which is perforated upon its upper face, and is formed with

20 a depression over which the bottoms of the cans or jars are placed, so as to leave a space under the bottoms of all of the cans or jars, so as to more readily heat the contents of the 25 jars and prevent their breakage.

Other objects and advantages of the invention will hereinafter appear, and the novel features thereof will be particularly pointed out in the appended claims.

30 The invention is clearly illustrated in the accompanying drawings, which with the letters of reference marked thereon, form a part of this specification, in which—

Figure 1 is a top plan of the attachment removed. Fig. 2 is a vertical longitudinal section through a wash-boiler with the attachment in position therein, and showing also in dotted lines the cans or jars supported upon the attachment. Fig. 3 is a vertical cross-section through the attachment, showing also in dotted lines portions of two jars thereon. Fig. 4 is a sectional view of the boiler provided with blocks or supports, upon which the steamer attachment, with flange omitted, rests 45 when in place.

Like letters of reference indicate like parts throughout the several views.

Referring now to the details of the drawings by letter, A designates my improvement. 50 It is shown in the present instance as of a shape and size adapted for use in connection with an ordinary wash-boiler; but in practice

it is proposed to make it of different shapes and sizes, according to the form of boiler with which it is desired to be used. It consists of 55 a perforated metal plate corresponding to but slightly smaller in size than the bottom of the boiler in connection with which it is to be used. It is provided with a supporting-flange a, so as to elevate it a short distance above 60 the bottom of the boiler. It is preferably stamped or pressed out of one piece of material, and, if desired, may be swaged to give strength thereto. The upper face of the steamer is provided with a depression b, which 65 forms a continuous channel around the upper face of the attachment, extending a short distance from the edge thereof, as seen best in Figs. 2 and 3. The perforations in the upper face extend centrally through this channel 70 and also upon both sides thereof, as clearly seen in Figs. 1 and 3.

The device is used as follows: It is placed within the boiler, as seen in Fig. 2, with about one and one-half inches of water. The jars 75 or cans filled with the fruit or the vegetables are then placed upon it. The boiler is then covered with its lid and heated until steam is generated. When the fruit or vegetables are sufficiently cooked, the jars are taken out, the 80 contents of one or two of them are used to replenish any shrinkage in the others, and they are then sealed and the operation is complete.

It is evident that instead of supporting the perforated and channeled steamer attachment 85 by an integral flange, the flange may be omitted, and the plate may rest upon blocks or supports in or attached to the inner sides or bottom of the boiler, as shown in Fig. 4, where the letters f f f represent blocks or supports, 90 on which the steam-heater rests when in use.

Importance is attached to the surrounding continuous depression or channel, as by its presence a steam-space is provided beneath the bottoms of the cans or jars, whereby the 95 jars are evenly heated and breakage avoided and the contents of the jars at this point subjected to direct influence of the steam, which it would not be if the metal were in close contact with the bottoms of the cans or jars.

What I claim as new is—

1. As an improved article of manufacture, a steamer attachment consisting of a plate having means of support and having its upper

face provided with a continuous annular depressed portion or channel, substantially as specified.

2. The steamer attachment described, consisting of a plate having a supporting-flange and having its upper face perforated and provided with a marginal and a central supporting portion, and an intermediate annular depressed portion, substantially as specified.

3. The herein-described steamer attach-

ment, consisting of a single piece of material and having a supporting-flange, and a perforated top having a continuous depression or channel, substantially as specified.

In testimony whereof I affix my signature in presence of two witnesses.

EDWARD P. ERICSON.
